CLAIM

The ornamental design for a cell phone repeater, as shown and described.

DESCRIPTION

FIG. 1 is a perspective view of our design;

FIG. 2 is a second perspective view thereof;

FIG. 3 is a first top view thereof;

FIG. 4 is a bottom view thereof;

FIG. 5 is a side view thereof, an opposite side being a mirror image of this view;

FIG. 6 is a first end view thereof; and,

FIG. 7 is an end view thereof showing a second end opposed to the first end.

The broken line showing of the environment is for illustrative purposes only and forms no part of the claimed design.
